(57) **CLAIM**

The ornamental design for a shingle, as shown and described.

DESCRIPTION

The patent file contains at least one drawing executed in color. Copies of this patent with the at least one color drawing will be provided by the Office upon request and payment of the necessary fee.

FIG. 1 is a top view of a shingle; and,

FIG. 2 is a top perspective view of the shingle of FIG. 1. Portions of the drawings shown in broken lines form no part of the claimed design.

1 Claim, 2 Drawing Sheets
(2 of 2 Drawing Sheet(s) Filed in Color)

FIG. 1

FIG. 2
